UNITED STATES PATENT OFFICE

EDFORD CARMICHAEL, OF WARRINGTON, ENGLAND, ASSIGNOR OF ONE-HALF TO THE
UNITED VELVET CUTTERS ASSOCIATION, LIMITED, OF MANCHESTER, ENGLAND

MACHINE FOR CUTTING THE PILE OF WEFT-PILE FABRICS

Application filed July 9, 1931, Serial No. 549,786, and in Great Britain July 11, 1930.

The invention relates to machines for cutting the pile of weft-pile fabrics, of the type in which the fabric in endless form is traversed past a stationary knife, carried by a holder which is fed laterally by means of a screw in order that the knife may operate on successive "races" from edge to edge of the fabric.

The invention has for its principal object 10 to provide an improved weft-pile cutting machine of the type referred to, in which the organization or arrangement of the elements or mechanisms constituting the machine will be such as to enable a considerable increase 15 in production to be effected.

Further objects of the invention, and which contribute to the attainment of the main object above referred to, include the provision 20 of improved means for arresting the travel of the fabric in the event of a stoppage being called for due to an abnormality in connection with the cutting, or to the end of a "race" being reached; the provision of improved means for ensuring that on occurrence of a 25 stoppage the stretch of fabric on which the cutting is taking place is maintained properly taut ready for recommencement of cutting; and the provision of improved means for passing back the fabric, after it has 30 passed the cutting position, towards the feeding or entering position.

The main feature characterizing the improved machine is that instead of the fabric being traversed beneath the cutting knife 35 in a substantially horizontal path, as has hitherto almost invariably been the case, it is caused to pass from an overhead roller to a lower roller so disposed in relation to the upper one that there is constituted between 40 the two rollers a stretch of fabric inclining at a suitable angle from the vertical. The rollers are driven to traverse the fabric downwardly and means are provided to retard the passage of fabric over the upper roller so 45 that the stretch of fabric referred to is under suitable general tension, additional local tension being provided in the usual manner by passing about the lower roller, beneath the fabric and in alignment with the cutting 50 point, an endless belt of relatively narrow

width, such belt being traversed laterally in synchronism with the lateral movement of the cutting knife. The member carrying the cutting knife is pivotal about and movable along an axis disposed suitably above the 55 upper roller and is so located that the usual holder for the knife guide bears against the face of the inclined cutting stretch of the fabric, at a point suitably adjacent the upper end of the stretch. The length of the cutting 60 stretch that is to say the distance between the upper and lower rollers, and the point in the stretch at which cutting takes place, is such that in combination with the means to be described for arresting the travel of the fabric, 65

the latter will, when a stoppage occurs due to an abnormality in connection with the cutting, be brought to rest before that point in the fabric at which the abnormality occurred has reached the bottom roller. The 70 operative is thus enabled to examine the fabric and restore normal conditions without any reversal of the machine and with much greater ease than in a machine of the usual construction, in which the cutting stretch 75 is horizontal. It will be apparent that in a machine of the said usual construction it is necessary for the cutting point to be located some distance towards the rear of the machine if the point in the fabric at which cutting 80 abnormality occurs is not to be carried past the usual front roller before the travel of the fabric is stopped. The cutting point is thus somewhat inaccessible to the operative both from the point of view of visual supervision and of reaching the knife for the purpose of shifting it from one race to the next or of replacing it in a race from which it may have jumped or become deflected. Furthermore, notwithstanding this somewhat inaccessible location of the knife the means hitherto provided to arrest the travel of the fabric have not sufficed to stop the fabric until the fault has reached such a position as 85 to render reversal of the machine necessary. These defects are entirely obviated in the improved machine, the knife being more conveniently located and reversal of the machine to restore normal cutting conditions after 90 stoppage due to cutting abnormality being, 95

as before mentioned, rendered unnecessary. Referring to the accompanying drawings,

Fig. 1 is a side elevation of the relevant parts of a machine constructed according to 5 and embodying the invention;

Fig. 2 is a front elevation of the machine, that is to say looking in the direction of the arrow A, Fig. 1;

Fig. 3 is a partial side elevation of the 10 machine from the opposite side of Fig. 1, and shows the method of driving certain of the parts; and

Fig. 4 is a detail hereinafter referred to.

Referring to the drawings the fabric F 15 is led up from an inclined receiving tray 1, and passed frontwardly about a tension roller 2 adjacent an overhead roller 3, such overhead roller being driven in known manner through a friction and ratchet device 4 20 which enables the belt 5, by which drive is conveyed to the roller, to continue moving when rotation of the roller 3 is prevented. An electro-magnetic brake 6, referred to again later, is provided in connection with 25 the roller 3.

A bar or rod 7 is provided adjacent the roller 3 on the front side thereof, and after having been led over the roller and such bar or rod the fabric is led down in an inclined path as shown to a lower front roller 8, which is controlled by a combined electro-magnetic clutch 9 and brake 9' which will 30 also be referred to again later. After passing beneath the lower roller 8 the fabric is led over a guide roller 10 and between the latter and a revolving brush 12, to fall on to the upper end of the inclined receiving tray 1.

The lower roller 8 is driven from any 40 suitable source such as an electric motor.

A screw 13, of suitable pitch and journaled at its ends in members attached to the side frames 14, 14 of the machine, has mounted upon it a nut block 15 to which is pivotally 45 attached, so as to be capable of swinging thereon, a rod or tube 16. The lower or opposite end of this rod or tube has pivotally attached to it an arm 17 carrying detachably a knife holder and guide 18 in known manner, a spring 19 being provided also in known manner to act upon the arm 17 and tend to swing it in a direction to carry the knife away from the fabric. A magnet 20 carried by an insulated attachment 21 on the 50 rod or tube 16 is adapted, when exerted, to attract an armature on the pivoted arm 17 and to hold the knife in cutting position against the action of the spring mentioned.

The nut block 15 on the overhead screw 18 60 forms a pivot about which the rod or tube 16 can swing in a vertical plane, and the angular weight of the rod or tube and of the parts carried thereby causes a bearer 22 on the rod or tube to rest upon the surface of 65 the downwardly inclined stretch of fabric

and position the knife relative to the fabric when the arm is in cutting position.

An endless belt 23 passes about the lower front roller 8 beneath the fabric opposite the cutting point and imparts local tension to the 70 stretch being cut. This belt passes at its rear part about a pulley 24 carried by a member 25 depending from a nut block 26 on a traverse screw 27, and a bridle 28 journaled on the pivot pin of the pulley 24 is connected by 75 a spring 29 to a nut block 30 on another traverse screw 31. The two screws 27 and 31 correspond in pitch to the overhead screw 13 on which the knife rod or tube 16 is carried, and the three screws are connected by a 80 common endless chain 32, see Fig. 3, so that the endless belt 23 is traversed synchronously with the lateral traverse of the knife. A hand wheel 33 fast on the screw 27 enables all three screws to be turned together to traverse the knife rod or tube 16 and belt 23. 85

The combined electro-magnetic clutch and brake 9 and 9' by which the lower front roller 8 is controlled is operated as follows:—A foot bar 34, pivoted at 34', has pivoted to it the 90 lower end of a rod or wire 35, and the upper end of this rod or wire is fashioned to provide a slot 35' in which registers a pin on a contact arm 36 pivoted at 36'. A contact member carried by this arm is adapted to 95 form the armature of a magnet 37 arranged in circuit with the magnet 20 which is adapted to hold the knife in cutting position.

The contact arm 36 is adapted to swing over a series of contacts 38 supplying current to the combined clutch and brake 9 and 9' and a spring 39 acts on the arm in a direction to cause it to make contact with the upper contact of the series 38, in which position current is cut off from the clutch but is 100 supplied to the brake. Depression of the contact arm 36 causes the brake current to be cut off and current to be supplied to the clutch, the passage of the arm 36 over the successive contacts of the series 38 controlling resistances of successively increasing values to permit the clutch to come gradually into operation. When fully depressed the contact arm 36 is attracted and held by the magnet 37 so long as the circuit through such 105 magnet is completed. If, however, the circuit is broken through abnormality in the cutting (suitable means being associated with the knife holder to cause the circuit through the knife holding magnet 20 to be broken on occurrence of any such abnormality) or by operation of the usual stop device 40 when the end of each race is reached, the contact arm is released by its holding magnet and is flung by its spring to the position 110 in which current is cut off from the clutch 9 and is supplied to the brakes 9'. The circuit including the magnets 20 and 37 is independent of those for the clutch and brake, which 115

are themselves also independent. 120

125

130

The circuit through the electro-magnetic brake 6 for the upper front roller 3 is also controlled by the contact arm 36. As the contact arm commences to move downwardly, to put the clutch 9 into action, it engages a contact 38' (see Fig. 4) so disposed that the engagement is effected before the arm has left the upper one of the series of contacts 38. The contact 38' is designed to close a circuit adapted to pass through the brake 6 a current of relatively low strength. When the contact arm is in its top position both the brakes 9' and 6 are fully applied. As the arm begins to move downwardly, the main current is cut off from the top brake and the bottom roller 8 commences to be revolved. During such commencement of rotation of the bottom roller, however, the top brake is still applied by the low power current, with the result that the stretch of fabric between the rollers 3 and 8 is drawn taut. As the contact arm descends further, to increase the speed of the lower roller 8, it moves clear of the contact 38' and the top brake 6 is fully released. When the contact arm is released by the magnet 37 and is moving upwardly it engages the contact 38' and causes the low power current to operate the top brake before the lower roller ceases to be driven and its brake is applied, and when the arm reaches its top position the main current is supplied to both brakes. The cutting stretch of fabric is thus always maintained taut.

To assist in the maintaining taut of the cutting stretch of fabric, a pivotally mounted transverse bar 41 having a yielding engaging surface is adapted to be pressed by a spring 42 against the back of the fabric as the latter passes about a roller 43 on its way to the tension roller 2. The pivot of the bar 41 carries a lever 44 one arm of which is acted upon by the spring 42 whilst the other arm is connected to one end of a rod 45 whose other end is hooked to form a slot 45' to engage the pin on the contact arm, the position of the hook or the lower end of the slot being such that when the contact arm is being lowered to put into action the clutch, the rod 45 is not pulled upon to release the fabric until the bottom roller 8 has commenced to rotate. The bar 41 maintains its gripping pressure against the fabric until the commencement of rotation of the bottom roller has drawn the fabric taut, the continued descent of the contact arm to rotate the lower roller at speed then drawing upon the rod 45 and swinging the bar 41 to inoperative position.

When the foot bar is released, after having been depressed to move the contact arm down into engagement with the magnet 37, the slots 35' and 45' in the connections 35 and 45 respectively, permit the bar to return to nor-

mal raised position and to leave the contact arm attracted by the magnet.

It has been stated that the fabric, after passing about the lower roller 8 and guide rollers 10 and 11, and having been acted upon by the rotating brush 12, drops on to the upper end of an inclined receiving tray 1, on which it collects in folds. To ensure the collected fabric passing down the tray, I provide a series of members 46 adapted to extend through and work in longitudinal slots in the top end of the tray. The members 46 are carried by a part 47 which is mounted pivotally between the side frames of the machine and is connected by a rod 48 with a crank arm 49 on a rotating disc 50. Each member 46 has pivotally connected to it a bar such as 51, the rear end of which rests and slides upon a transverse cross bar 52. As the members 46 are swung rearwardly, the rear ends of the bars 51 ride up on the cross bar 52 and their front ends are elevated. The rearward movement of the bars thus causes the fabric resting in the tray to be raised and carried rearwardly down the tray, the bars as they move forward again being lowered and depositing the fabric in the position to which it has been moved.

The point at which the cutting knife engages the fabric is so disposed in relation to the lower roller 8, and the stop and brake mechanisms are so designed, that when the machine is being stopped the fabric is brought to rest before the end of the cut portion (or the join of the fabric as the case may be) has reached the level of the lower roller. The placing of the cutting knife into a new race, or its replacement into the race being cut can thus be performed without any turning back of the fabric.

An upward projection 53 from the nut block 26 is bent rearwardly over the rod 7 to assist in placing additional tension on the portion of fabric being cut, such projection 53 being traversed along the rod synchronously with the movements of the endless belt 23 and of the cutting knife.

The details of construction and arrangement of the parts employed in the several co-operating mechanisms are capable of modification from the particular embodiment illustrated, so long of course as the downwardly-inclined path of the cutting stretch of fabric and the position relative thereto in which the knife rod or tube is mounted are preserved.

Having thus described my invention, what I claim as new and desire to secure by Letters Patent is:—

1. In a machine for cutting weft-pile, an upper roller and a lower roller about which the fabric is passed, the lower roller being so set in relation to the upper that the stretch of fabric between them inclines downwardly and forwardly, an overhead screw on which

a rod or tube is mounted pivotally and means for driving said screw, a cutting knife carried by an arm mounted pivotally on said rod or tube and adapted to engage the fabric 5 at a point adjacent the upper end of the inclined stretch, and means operative in case of abnormality in connection with the knife to withdraw the knife from the fabric and to stop the traverse of the latter before the 10 point at which cutting stopped reaches the lower roller.

2. A machine according to claim 1 wherein retention of the knife in cutting position and continued running of the machine depends upon continuity of an electric circuit, and wherein means are provided not only for breaking such circuit on occurrence of a cutting abnormality but also when the join between two portions of fabric is approaching 15 the knife.

3. In a machine according to claim 1, an endless belt passing about the lower roller beneath the portion of fabric being cut and about a pulley carried by a part depending 20 from a transverse screw, a bridle associated with said pulley being acted upon by a spring connected to a nut block on another transverse screw to hold said belt taut, and means being provided to rotate the two screws referred to synchronously with that on which 25 the knife rod or tube is mounted.

4. In a machine according to claim 1, an endless belt passing about the lower roller beneath the portion of fabric being cut and about a pulley carried by a part depending 30 from a transverse screw, a bridle associated with said pulley being acted upon by a spring connected to a nut block on another transverse screw to hold said belt taut, and an 35 upward projection from the nut block from which the bridle pulley is suspended, said projection being bent rearwardly at its upper end over a transverse rod disposed adjacent the roller at the upper end of the cutting stretch for the purpose of co-operating 40 with the endless belt to provide additional local tension on the portion of fabric being cut.

5. In a machine according to claim 1, a 45 combined electro-magnetic clutch and brake controlling rotation of the lower roller about which the cutting stretch of fabric passes, the circuits through such clutch and brake being controlled by a contact arm operable by a 50 pivoted footbar.

6. In a machine according to claim 1, a 55 combined electro-magnetic clutch and brake controlling rotation of the lower roller about which the cutting stretch of fabric passes, 60 a contact arm operative to control the circuits through said clutch and brake, a pivoted foot bar operable to move said contact arm, and an electro-magnetic brake for the roller about which the fabric passes at the upper end of 65 the cutting stretch, said last-named brake

being also controlled by the contact arm in such a manner that when the clutch for driving the bottom roller is being put into action the main current is first cut off from the top brake and a relatively low-power current supplied to the said brake until such time as the lower roller has commenced to revolve slowly whereupon said low-power current is also cut off, whilst when the clutch is being put out of action the low-power current applies the top brake a short time before the clutch ceases to drive and is then cut off and the main current permitted to apply fully the brakes for both the top and bottom rollers. 70

7. In a machine according to claim 1, a 75 combined electro-magnetic clutch and brake adapted to control rotation of the roller about which the fabric passes at the lower end of the cutting stretch, a contact arm controlling the circuits through said clutch and brake, a magnet designed to hold the contact arm in a position to drive the said lower roller at speed so long as cutting proceeds normally, but to release said contact arm when an abnormality occurs, and a spring operative on 80 release of the contact arm to move the said arm to a position in which the clutch is withdrawn and the brake applied to the bottom roller, and a brake also applied to the roller about which the fabric passes at the upper 85 end of the cutting stretch. 90

8. In a machine according to claim 1, a 95 roller about which the fabric is passed on its way to the upper end of the cutting stretch, a spring-actuated bar adapted to bear against 100 said roller and apply braking-pressure to the fabric, means for controlling traverse of the fabric, and means operated by said control means whereby when the fabric is at rest or travelling slowly the bar is permitted to apply braking pressure to the fabric, and when the fabric is travelling quickly the said bar is moved to inoperative position. 105

9. In a machine according to claim 1, a 110 guide roller and a rotating brush between which the fabric is led after having passed about the roller at the lower end of the cutting stretch, an inclined tray disposed beneath said brush on to the upper end of which the fabric is permitted to fall, longitudinal 115 slots in the upper end of the base of said tray, and bars working in said slots, said bars being pivoted to a depending pivoted member to which frontward and rearward swinging movements are given, as and for the purpose 120 set forth.

In testimony whereof I affix my signature.
EDFORD CARMICHAEL.
